(54) **PLOUGH**

(76) Inventor: **George D. Avery**

George L. Avery
Letters Patent

The Schedule referred to in these Letters Patent and making part of the same containing a description in the words of the said George L. Avery himself of his improvement in the Plough.

In my patent dated Dec. 28th 1818 for an improvement in the Plough I specified the main and brace bolts in the following words and figures viz. "The main and brace bolts are rough-hewn. — the main bolt is $\frac{3}{4}$ of an inch diameter, its lower end is bent in the form of a hook to fit the brace bar on which it is inserted the head standing forward from the brace bar; the bolt extends up perpendicular through the hole left for that purpose in the top and through the beam. The brace bolt is $\frac{1}{2}$ of an inch diameter and goes slanting up through the handle, through the hole made for it, and through the beam; both bolts have strong screws on their upper ends by which they secure the beam to the body of the plough." In the bolt through the handle and beam as specified in my said patent, may be left out, because the plough is sufficiently strong without it. The upper hand part of the land side, specified in my said patent, should be left out, so as to leave the upper face part of it for a part of the upright, which should extend up about $15\frac{1}{2}$ inches above the lower edge, to the beam which should be straight on its under and land sides, the upright should be about $2\frac{1}{4}$ inches thick at its upper end. The top plate specified in my said patent, should also be left out, except the fore end of the top plate, which is left to extend back, from the upper end of the upright about $1\frac{1}{2}$ inches, and should be about one inch thick, and have a hole up through it for the brace bolt, which is put up close to the land side of the upright, which should be fluted to admit the bolt to stand at or near the centre of the upper end of the upright. The upper hand part of the land side and the top plate were cast entire with the plough but first to strengthen it, and they did strengthen it greatly, but as the plough is sufficiently strong without them, they are therefore left out. The brace bolt should be $\frac{3}{4}$ of an inch diameter, and long enough to go up through the beam and nut, the lower end of it is bent to fit the casting to this the bolt passing through; or there may be a head on the lower end of the bolt to fit the nut.

ings; or the lower end may be larger and taper upwards; that part of the lower end which is in the hole may be square or round; and the hole must be made accurately, so that the bolt will fit it. In my said patent I specified the brace bar to brace between the land side and mould board in the following words and figures viz, "The brace bar is of iron, about one inch square; it goes through the land side and mould board 24 inches above their lower edges and in the proper place to receive the bolt on the lower end of the main bolt. The use of the brace bar is to brace between the mould board and land side, and to secure the body of the plough to the bar by its connection with the main bolt." In the castings of my ploughs, which were made in the year 1818, I had holes cast for the brace bars and riveted them in; after considerable experience in rivetting them in, I found that they might be cast in, either of wrought or cast iron. In December 1818 I wrote the specification of my patent, which was dated as aforesaid, 23rd December, 1818, in which I described the brace bar, the situation where it should be placed, and its use; but being then unacquainted with specifications, and with the patent law and never having written a specification before, I omitted to describe the manner of fastening the brace bar in, therefore believing myself justly entitled to the patent of the brace bar, to brace between the land side and mould board in in that manner to strengthen and improve the plough, I specify an improvement on my said patented improvement of the plough as follows, viz. The brace bar to brace between the land side and mould board of the plough, to be of cast or wrought iron and cast in the land side and mould board at its ends, at about 24 inches above their lower edges, and about 8 inches from the heel of the plough to the brace bar, if of wrought iron, may be riveted in. When a wrought brace bar is to be cast in, it should be cut to the proper length, and the ends made rough to hold it fast in the casting. The manner of casting in, and rivetting in, the brace bar to brace between the land side and mould board to strengthen and improve the plough, as lastly herein before specified. I claim as my invention and improvement

Witness,

George D. Avery,
